HARRY H. MCKEE AND NICKOLAS J. DZIEDZIC, OF CHICAGO, ILLINOIS, ASSIGNORS, BY
MESNE ASSIGNMENTS, TO INDUSTRIAL PATENTS CORPORATION, OF CHICAGO, ILLINOIS, A CORPORATION OF DELAWARE

CONVEYER

Application filed July 30, 1931. Serial No. 553,983.

The present invention relates to conveyer devices and more in particular to conveyer devices adapted for use with slicing machines.

Among the objects of the present invention is to provide a conveyer device for sliced meat, or the like, which may be easily wrapped thereon without the necessity of touching the same with any part of the human body. In preparing certain cuts of meat, as for example, sliced bacon and the like, precautions are taken by certain of the packing houses to prevent direct contact of the bacon by the employees, thus eliminating to a large degree any possibility of mold forming thereon. Such pieces or cuts of meat are handled with suitable instruments or devices, and placed upon a piece of wrapping material preliminary to the weighing of the same and the further step of placing 20 of them in suitable cartons or containers.

Heretofore, pieces or groups of slices moving on a conveyer, as for example, have been rather hard to handle, inasmuch as it has been difficult to grasp the slices and to place 25 the same on a piece of wrapping material to be further moved about thereon and in a suitable position to facilitate the further rapid packaging of the same.

It is therefore an object of the present invention to provide a novel conveyer means so constructed that a piece of wrapping material may be placed over the slices, or groups thereof, and folded around the ends thereof so that the same may be easily handled with 35 the wrapper during the movement thereof over the conveyer, as likewise during the successive steps in the packaging of these groups.

In the embodiment selected to illustrate the invention, the conveyer means is provided 40 with a conveyer table having marginal portions below the central portion thereof upon which conveyer elements are provided for movement of the slices thereover and in overhanging relation thereto and the marginal 45 portions of the table therebelow. A piece of wrapping material may be placed on the slices and folded around the ends thereof because of the disposition of the marginal portions of the table, after which the slices, or 50 groups thereof, may be gripped and turned

in a position ready for packaging, such operations being all effected during movement of the slices over the conveyer means.

Other objects, capabilities, advantages and features are comprehended by the invention, 55 as will later appear and as are inherently possessed thereby.

Referring to the drawing;

The figure is a fragmentary view in perspective of a conveyer unit embodying the 60 present invention.

Referring now more in detail to the drawing, an embodiment selected to illustrate the present invention is disclosed as comprising a conveyer table 2 supported in any suitable 65 manner as by means of the legs 4 and having a plurality of conveyer elements 6 movable thereover for conveying material, such as groups of slices of bacon 8, over the surface thereof.

In the packing and wrapping of certain meats, such as slices of bacon, certain of the packing houses prohibit the handling of the slices other than by instruments or with wrapping paper secured thereto, because of 75 the danger of starting mold which is detrimental to the appearance of the meat.

The present invention is concerned more particularly with the conveying of slices of bacon from a slicing machine to a point where 80 the operators wrap these slices and prepare the same for sale. The table 2 is formed with a substantially U-shaped central portion 10 having its upper surface for the movement of the conveying elements 6 thereover, and being provided with marginal flanged portions 12 below the surface of the central portion 10. The conveyer elements pass over sprockets 11 mounted upon a transverse shaft 13 journaled in bearing blocks 15. These bearing blocks are mounted upon the ends of the threaded shafts 17 which are adjustably mounted in the blocks 19 fitting between the lugs 21 and downwardly extending flanges 23 of marginal portions 12, these sprockets being adjacent an opening 25 in the central portion 10.

During the movement of the groups of slices of bacon 8 over the table 2, the ends thereof may overlap or overhang the margin- 100

nal portions 12 of the table, whereby a piece of wrapping material, such as cellophane, glassine, waxed paper, or the like 14, may be positioned thereon and folded around the overhanging ends of the slices, after which the slices may be turned by the operators positioned near this conveyer, so that the slices rest upon the wrapping material. When this has been done, the remaining operations necessary to properly wrap the slices of bacon may be easily and effectively accomplished without necessitating the contact of the operator's hands or other parts of the body with the slices of bacon.

15 While we have herein described and upon the drawing shown an illustrated embodiment of the invention, it is to be understood that the invention is not limited thereto but may comprehend other constructions, arrangements of parts, details and features without departing from the spirit thereof.

Having thus disclosed the invention we claim:

1. A conveyer device, comprising a conveyer table having a central raised portion, and conveyer elements movable over said raised portion.

2. A conveyer device comprising a conveyer table provided with a central conveying surface, conveyer elements movable over said surface, the margins of said table being disposed below said surface.

3. A conveyer device comprising a conveyer table having a central conveying surface, said table having marginal edge portions disposed in planes below said central surface, and conveyer elements movable over said surface.

4. A table for a conveyer device, comprising a channel-shaped central conveying portion, and dependent laterally extending flanges.

5. A conveying device comprising a table having a conveying surface, conveyer elements movable over said surface, the marginal portions of said table being below said central portion, whereby wrapping material can be folded over the ends of material overhanging said marginal portions.

50 6. A conveyer device comprising a conveyer table, conveyer elements movable over said table for movement of non-rigid material overhanging the edges thereof, and means for supporting said overhanging portions of said material whereby the same may be grasped and moved as desired.

60 7. A conveyer device comprising a conveyer table having a raised central conveyer surface, the marginal portions of said conveyer table being flanged and disposed below said surface, said surface having openings therein, conveyer elements movable over said surface and passing through said openings, and means mounted in said flanges adjacent

said openings for passage of said elements thereover.

8. A table for a conveyer device, comprising a channel-shaped central conveying portion, and laterally extending flanges in a 70 plane below the plane of said portion.

Signed at Chicago, in the county of Cook and State of Illinois, this 28th day of July, 1931.
